UNITED STATES PATENT OFFICE.

CHARLES E. PAGE, OF LOS ANGELES, CALIFORNIA, ASSIGNOR, BY DIRECT AND MESNE ASSIGNMENTS, TO ECONOMY DISPENSER CORPORATION, OF LOS ANGELES, CALIFORNIA, A CORPORATION OF NEVADA

DISPENSING DEVICE.

Application filed January 15, 1927. Serial No. 161,332.

This invention relates to a dispensing device such as used for dispensing small quantities of groceries in bulk or other commodities. While the dispensing device may 5 be used for dispensing any kind of food or other substance, in the present specification I have described an embodiment of the device which is particularly adapted for dispensing ground coffee or other granular material. The type of dispensing device to 10 which my invention relates includes in its construction a curved closure mounted upon a shaft and which swings across the outlet from the receptacle for the material to be 15 dispensed. The device also includes a second closure, and the movements of these closures are correlated so that when one is open the other is closed, and vice versa.

The general object of my invention is to 20 improve the general construction of a dispensing device of this type and particularly to provide improved means for securing the curved closure to its shaft, and for connecting the closures to cause them to operate in 25 a correlated manner.

Further objects of the invention will appear hereinafter.

The invention consists of the novel parts 30 and combination of parts to be described hereinafter, all of which contribute to produce an efficient dispensing device.

A preferred embodiment of the invention is described in the following specification, while the broad scope of the invention is 35 pointed out in the appended claims.

In the drawings:

Figure 1 is a vertical section through the lower end of a dispensing device embodying my invention, the upper portion of the 40 dispensing device being broken away.

Figure 2 is a plan of the head or bottom of the dispensing device removed from the body of the device.

Figure 3 is a vertical section taken about in the plane of the line 3—3 of Figure 1.

Figure 4 is a detail partially broken away and shows the shaft of the device in section on the line 4—4 of Figure 2.

Referring to the parts, 1 represents the 50 container for the material or substance to be dispensed, for example, coffee. In applying my invention, I provide a removable head or bottom 2 for this container, said head having an outlet 3 which is preferably

of tubular form. This outlet extends down 55 from the head 2 which is of curved or cup form. The head and tubular outlet 3 are preferably made of light sheet metal.

According to my invention I provide a closure for the outlet which is mounted to 60 rotate on an axis extending transversely to the longitudinal axis of the outlet; that is to say, extending transversely through the vertical axis passing through the outlet; this closure has a curved face which is adapted to 65 engage the edge of the inner end of the outlet. The face of the closure is curved in two directions so that the closure may sweep across the outlet and engage the edge of the outlet with its convex face. In this way the 70 contact between the closure and the outlet is not formed between the faces of two plates but between the edge of the outlet and the face of the closure.

In order to accomplish this I provide a 75 closure 4 which is preferably formed of a plate of sheet metal bent into the form of a sector. The sector is substantially a half circle in form. That is to say it extends through 180°. The sector includes also a 80 chord plate 5 which connects the ends of the curved plate of the sector. For this purpose the ends of the chord plate are formed with slots 6, and the ends of the curved plate of the closure are bent around and hooked into 85 these openings 6 from the upper side. See Figure 1. This sector 4 is attached to a transverse shaft 7 which extends horizontally through the head 2. In order to secure the sector to the shaft I prefer to form the 90

chord plate with two integral straps 8 which pass over the upper side of the shaft and an integral strap 9 which passes under the lower side of this shaft. In addition to this the shaft is formed with a neck 10 of reduced 95 dimensions and this neck is flattened or mutilated so as to present a flat face 11 which is engaged by the strap 9. In this way two shoulders 12 are formed which engage the edges of the strap 9 and this keeps the closure from moving longitudinally on the shaft. The neck 10 by reason of the flat face 11, has a D form that operates to fix the sector on the shaft so that it will swing over the opening or outlet 3 when the lever 13 of the shaft is actuated. This type of closure 100 is very effective as a closure for a dispensing device and it will operate effectively on a 105

granular substance such as sugar or ground coffee. This form of closure and co-operating outlet avoids the use of two surfaces which come together and between which the fine grains of the material may become lodged.

In adapting a closure of this kind to a dispensing device to dispense a given or measured quantity, I provide the lower end of the outlet 3 with a closure 14. This closure is in the form of a disc which is attached at one edge so that it can swing or rotate on an axis extending substantially parallel to the axis of the outlet and at right angles to the shaft

15 7. In the present instance the edge of this disc 14 is attached to a vertical shaft 15 which is rotatably mounted in the head 2 and extends up into the head at the side of the outlet, see Figure 3.

20 Between the closures 14 and 4 I provide a connection which operates to insure that when one of the closures is open the other one will be closed. For this purpose I provide a rigid arm 16 carried by the upper 25 end of the shaft 15, said arm having a longitudinal slot 17. Moving with the shaft 7 I provide a dog to co-operate with this arm 16. For this purpose I provide an extension or dog 18 which may be formed integral with 30 one edge of the sector of the closure 4 and this finger or dog 18 projects up into the slot 17. With this organization of parts it will be evident that the movements of the closures 4 and 14 are correlated. The arm 35 16 and the dog 18 are so positioned that when the disc 14 has closed the lower end of the outlet 3, the closure 4 will be in an open position and vice versa.

In the normal position of the closures the 40 disc 14 will be in alignment with the lower end of the outlet 3 and the closure 4 will be in an open position. That is to say the upper end of the outlet will be in communication with the interior of the receptacle 45 1. At this time the lever 13 will be in a position substantially 180° from that in which it is shown in Figure 1. By rotating the lever around to the position indicated in Figure 1 the closure 4 will operate to 50 close the upper end of the outlet 3 and at the same time the dog 18 will actuate the arm 16 to swing the lid or closure 14 to its open position, and this is indicated in dotted lines in Figure 2.

55 The opening movement of the closure 14 is finally arrested through the agency of a stop finger 19 which projects laterally from the arm 16. This stop finger strikes the inner face of the head 2 and in this way 60 stops the opening movement.

The movement of the lever in this direction is resisted by coil spring 20, see Figure 3, which is disposed around the shaft 7. One end of this spring is held in a small socket 65 21 formed on the inner side of the head 2,

and the other end is fixed to a pin 22, projecting from the side of the shaft. In other words, the spring exerts its force in the direction to hold the closure 14 closed. In order to limit the closing movement of the closure 14, one edge of this closure is provided with a small projection or nib 23 which engages the lower end of the outlet 3 when the disc 14 is completely closed and in this way prevents further movement of the lid.

70 The lever 13 may be made integral with the shaft 7. In placing the shaft 7 in position its end is passed through an opening 24 in the side of the head 2 near the shaft 15 and the end of shaft 7 which is rounded, is received in a small socket 25 which is off-set 80 outwardly in the wall of the head 2 on the opposite side.

85 In order to retain the shaft 7 it is provided with a reduced neck at the point 25 and around this neck a split ring or washer 26 is received. This washer prevents the shaft from moving outwardly through the opening 24. The details of this construction 90 are illustrated in Figure 4.

95 It is understood that the embodiment of the invention described herein is only one of the many embodiments this invention may take, and I do not wish to be limited in the practice of the invention, nor in the claims, to the particular embodiment set forth.

What I claim is:

1. In a dispensing device, the combination of a receptacle having an outlet, a closure for the outlet mounted to rotate on an axis extending transversely to the longitudinal axis of the outlet, said closure having a curved face adapted to engage the edge of the inner end of the outlet, a closure in the form of a disc seating on the outer end of the outlet and mounted to rotate on an axis extending substantially parallel with the longitudinal axis of the outlet, an arm rigid with the second named closure and an actuating dog rigid with the first named closure to engage the said arm and co-operating with the same to close the outlet with the inner closure before the outer closure opens the outlet, said arm having a stop projecting laterally therefrom to limit the movement of the first named closure.

110 2. In a dispensing device, the combination of a receptacle having an outlet, a closure for the outlet mounted to rotate on an axis 120 extending transversely to the longitudinal axis of the outlet, said closure having a curved face adapted to engage the edge of the inner end of the outlet, a closure in the form of a disc seating on the outer end of the outlet and mounted to rotate on an axis 125 extending substantially parallel with the longitudinal axis of the outlet, an arm rigid with the second named closure, and an actuating dog extending up from the first named 130

- closure to engage the said arm and cooperating with the same to close the outlet with the inner closure before the outer closure opens the outlet.
5. 3. In a dispensing device, the combination of a receptacle having an outlet, a closure for the outlet mounted to rotate on an axis extending transversely of said outlet, said closure consisting of an elongated cup shaped plate having an approximately spherical convex surface, said plate having its greater dimension transverse to the axis of rotation and having its transverse curved surface engaging the walls of receptacle 10 about said outlet when in closed position, a closure for the outer end of the outlet mounted to rotate on an axis and having an arm for actuating the same, and a rigid dog moving with the first named closure when it rotates on its axis, for engaging the arm and co-operating with the arm to close the inner closure before the outer closure is open.
- 20 4. In a dispensing device, the combination of a receptacle having an outlet, a transverse shaft above the outlet, a closure having a sector shaped plate and a chord-plate connecting the ends of the sector shaped plate, said chord-plate having integral straps struck therefrom encircling the shaft and 25 securing the sector thereto.
- 30 5. In a dispensing device, the combination of a receptacle having an outlet, a transverse shaft above the outlet, a closure having a sector shaped plate and a chord-plate connecting the ends of the sector shaped plate, said chord-plate having integral straps struck therefrom encircling the shaft and 35 securing the sector thereto, said shaft having a neck of reduced dimensions at said straps whereby shoulders are formed at each side 40 of said neck to secure the closure against longitudinal movement on the shaft.
6. In a dispensing device, the combination of a receptacle having an outlet, a transverse shaft above the outlet, a closure having a sector shaped plate and a chord-plate connecting the ends of the sector shaped plate, said chord-plate having integral straps struck therefrom encircling the shaft and 45 securing the sector thereto, said shaft having a neck of reduced dimensions receiving said straps and having a flat face at said neck for securing the closure on the shaft.
7. In a dispensing device, the combination of a receptacle having an outlet, a closure 50 for the outlet mounted to rotate on an axis extending transversely to the longitudinal axis of the outlet, said closure having a curved face adapted to engage the edge of the inner end of the outlet, a closure in the 55 form of a disc seating on the outer end of the outlet and mounted to rotate on an axis extending substantially parallel with the longitudinal axis of the outlet, an arm rigidly secured to the second named closure and having a slot extending substantially radially from the axis of rotation of the second named closure, and a dog integral with the first named closure and extending up from the edge thereof to engage said slot so that 60 said dog and said slot co-operate to close the outlet with the inner closure before the outer closure opens the outlet.

Signed at Los Angeles, Calif., this 4 day of Jan., 1927.

CHARLES E. PAGE.
